UNITED STATES PATENT OFFICE.

EDWARD M. EGER AND RALPH D. KLEAR, OF PLEASANT BEND, OHIO.

POULTRY-CRATE.

1,242,160.

Specification of Letters Patent.

Patented Oct. 9, 1917.

Application filed April 7, 1917. Serial No. 160,498.

To all whom it may concern:

Be it known that we, EDWARD M. EGER and RALPH D. KLEAR, citizens of the United States, and residents of Pleasant Bend, in 5 the county of Henry and State of Ohio, have invented a certain new and useful Poultry-Crate; and we do hereby declare the following to be a full, clear, and exact description of the invention, such as will enable 10 others skilled in the art to which it appertains to make and use the same, reference being had to the accompanying drawings, and to the characters of reference marked thereon, which form a part of this specification. 15

This invention relates to collapsible crates or packing cases, and particularly to a crate of this character adapted for the shipping of poultry.

20 The primary object of our invention is the provision of a simple and efficient collapsible crate of the character described composed of few parts and capable of being easily and quickly set up or collapsed and 25 capable of being locked in either of said forms. Further objects and advantages of the invention will be apparent from the following detailed description thereof.

While the invention, in its broader aspect, 30 is capable of embodiment in numerous forms, a preferred embodiment thereof is illustrated in the accompanying drawings, in which,—

Figure 1 is a perspective view of a crate 35 in set-up form embodying our invention. Fig. 2 is a perspective view of the crate in collapsed form with the top member and locking means removed, and Fig. 3 is an enlarged fragmentary detail in perspective 40 of one corner portion of the crate in set-up position.

Referring to the drawings, 1 designates the bottom member of the crate which is preferably, but not necessarily, of imperforate material, to the top of which adjacent to the respective ends and side edges are hinged the opposed ends 2, 2 and the opposed sides 3, 3 for inward collapsing movements, the sides being adapted to fold inward over the ends 2, as shown in Fig. 2. 50 These sides and ends may be of grated or open form, as shown.

Each side 3 is provided at each end thereof adjacent to its upper edge with an inwardly turned tongue or hook 4, which parallels the sides and is adapted to fit into a

registering opening 5 in the adjacent end 2. It is thus evident that the ends 2, 2 are prevented from swinging outward from set-up position and that the sides 3, 3 are prevented from swinging both inward and outward from set-up position.

The top member of the crate comprises two sections 6 and 7 which are hinged together at their inner ends, preferably at the longitudinal center of the crate, as at 8, to permit an outward bowing or breaking of the top member to facilitate an insertion of the end spurs 9, which are provided at the outer ends of the top member, into or a removal of the same from registering openings 10 in the upper edge portions of the ends 2, 2. The top is provided in spaced relation at its side edges with hooked tongues 11 for engaging over the top edge of the respective sides 3, 3 to support the top member in countersunk relation to the top edges of the sides and ends of the crate. In the present instance each section of the top member is provided with two lugs 11 at each side thereof.

The top member of the crate is provided in its center with an opening 12 which extends partly into each section 6 and 7 and is closed by a door 13 which is hinged to one end thereof, as at 14. The free end of the door 13 when in closed position rests on a spur or tongue 15 projecting from the adjacent end wall of the opening 12. A latch member 16 is hinged to the section 7 at the free end of the door 13 and is adapted to be swung over the free end portion of the door 13 to hold it in closed position, as shown in Fig. 1.

When the crate is in set-up position with the top member 6, 7 thereof in place, a rod 17 is inserted through openings 18 in the sides 3, 3 adjacent to their top edges and extends across the top member of the crate adjacent to the center thereof and through the looped free end of the latch member 16, thereby retaining all of the parts in closed or locked position. The rod 17 is capable of being removed in only one direction through the openings 18, and the end thereof, which is drawn through the openings is provided with an eye for receiving the padlock 19, which retains the rod in locking relation to the crate. It is thus evident that the rod 17 not only retains the top member of the 110 crate in assembled relation to the sides and ends thereof but also coöperates with a

latch member 16 to retain the door 13 in closed position.

When the crate is collapsed the sides and ends thereof are folded inward with the 5 sides disposed outermost and the top member 6, 7 is then placed over the same with two of the end spurs 9 extending into registering apertured ears 20 which are fixed to and rise from the respective end edges 10 of the bottom 1 at the outer sides of the respective end members 2. The rod 17 is then inserted through apertured ears 21, which are fixed to and rise from the side edges of the bottom 1 near the center thereof and 15 without the side members 3, 3, said rod extending over the central portion of the top member 6, 7 to secure all of the parts in assembled collapsed relation.

It is evident that our improved crate is 20 capable of being easily set up or knocked down and that when in collapsed form is capable of being compactly packed for storage or shipment. For durability and cheapness of construction the bottom, sides, 25 ends and top member are preferably composed of sheet metal with the sides, ends and top member preferably provided with grated openings.

We wish it understood that our invention 30 is not limited to any specific construction, arrangement or form of the parts, as it is capable of numerous modifications without departing from the spirit of the claim.

Having thus described our invention,

what we claim as new and desire to secure 35 by Letters Patent, is—

In a crate of the class described, a bottom, side and end members hinged to said bottom for inward folding movements thereover, said members having interlocking hooked 40 engagement at their end edges when in set-up relation and the end members having openings in their top edge portions, a top member disposed in countersunk relation to the top edges of the side and end members and having spurs at opposite ends for insertion into said end openings and having parts at its side edges for engaging over the top edges of the side members, said top member being jointed intermediate its ends 45 to permit an outward breaking thereof and having a door opening extending on both sides of such joint, a door hinged in said opening at one end thereof, a latch member hinged to the top member at the other end 50 of said opening and adapted to lie over the free end of said door to hold it in closed position and having an opening in its free end, a rod extended through the top edges of the side members over the top member 55 and door and through the free end of the latch member to retain the parts in assembled closed relation, and means for securing said rod in locked position.

In testimony whereof, we have hereunto 60 signed our names to this specification.

EDWARD M. EGER.

RALPH D. KLEAR.
